UNITED STATES PATENT OFFICE.

AZEL C. HOUGH, OF JANESEVILLE, WISCONSIN, ASSIGNOR TO HOUGH SHADE CORPORATION, OF JANESEVILLE, WISCONSIN, A CORPORATION OF CONNECTICUT.

SHADE CONSTRUCTION.

Application filed December 15, 1923. Serial No. 680,958.

To all whom it may concern:

Be it known that I, AZEL C. HOUGH, a citizen of the United States of America, and a resident of Janesville, in the county 5 of Rock and State of Wisconsin, have invented a new and useful Shade Construction, of which the following is a specification.

My invention relates to improvements in 10 shades, of the woven-slat type and commonly known as porch shades, and resides in a construction wherein combined overlapping and spacing or separating, auxiliary slats or weft units are incorporated 15 with the ordinary slats or weft units, such auxiliary weft units being of a character and so arranged relative to the other weft units that light is prevented from passing through the structure, but air is not excluded, all as 20 hereinafter set forth.

Many ineffectual and unsuccessful attempts have heretofore been made to produce a shade construction which would exclude the light without excluding the air. 25 Such a shade construction I have now produced, and the primary object of my invention resides in such production. In this shade construction light from any angle impinges on some part of the non-reflecting 30 wood, of which the weft units consist, and consequently is prevented from passing through from one side to the other of the structure, and this in spite of the fact that the weft units are spaced apart or separated 35 by portions of the warp units which are located between said weft units, and air is permitted freely to circulate through the interstices thus formed.

A further object is to provide a shade 40 construction of this character which can be rolled and unrolled like the ordinary shade construction, although on one side only, this alone being necessary. The introduction of 45 my construction into a shade does not, therefore, impair the usefulness of said shade, or interfere with the necessary functioning of the same.

Another object is to produce a light-proof 50 shade construction which may be utilized in part or in whole in the manufacture of shades of the woven-slat type, of which the following are examples: A shade which is light proof in its entirety; a shade which is light proof only in part, or which has light- 55 proof parts less than the whole; a shade

which has a light-proof part or parts, another part or parts of ordinary formation, and a part or parts of so-called ventilating character, wherein the weft units are spaced farther apart than in the ordinary formation; and a shade which has only ventilating 60 and light-proof portions.

These and other objects and advantages I attain by the means illustrated in the accompanying drawings, in which—

Figure 1 is a side elevation of a fragmentary portion of a woven-slat shade which embodies a practical form of my light-proof construction; Fig. 2, an end elevation of 65 said shade construction; Fig. 3, an elevation 70 of the opposite side of the portion of shade shown in the first view; Fig. 4, a vertical section through said portion of said shade, said section being taken through slotted parts of the combined overlapping and spacing weft units; Fig. 5, a perspective, sectional view of a fragment of one of said combined overlapping and spacing weft units; Fig. 6, a perspective view of a complete shade which has at the bottom a light- 75 proof section and at the top a ventilating section, and, Fig. 7, a similar view of a shade which is of ordinary construction except in the lower portion where there is a light-proof section, the intermediate portion 80 of the shade being omitted.

Similar reference characters designate similar parts throughout the several views.

Figure 1 is an outside elevation, and Figs. 3, 6, and 7 are inside elevations, inasmuch as 90 the new shade construction can be rolled, to the best advantage at least, as will hereinafter more fully appear, only on the side presented in said last-named views, and porch shades are rolled on the inside.

An ordinary slat shade consists of a plurality of weft units made of thin wooden strips or slats, as 1, and a plurality of warp units made of fabric strands or cords, as 2, the intermediate warp units generally comprising two cords and the end warp units four cords, although these numbers may be varied. The weft units 2 are interwoven with the warp units 1, passing on opposite sides of and between said weft units. The same method of interweaving is preferably employed in connection with the new shade construction. I do not, however, desire or intend to limit myself to the aforesaid method, inasmuch as any practical method 105 110

of interweaving the weft units with the warp units, or practical form of warp weave, may be employed or substituted for the other without materially changing or modifying the invention. Usually a shade is provided at the top and bottom with mouldings each of which is made up of the top or bottom weft unit 1, as the case may be, and additional slats 3-3 secured to such weft unit on opposite sides thereof. The weft units 1 may be wide or narrow, as desired. Sometimes both wide and narrow weft units are present in the same shade.

Frequently it is desired to provide a shade 15 with special ventilating means, and, in such event, the weft units 1 are spaced apart to a greater extent than in the ordinary or more common weave or construction. This extra wide spacing may be effected by crossing the warp units 2 between the weft units 1, and twisting the two strands of each warp unit together one or more times as may be necessary, instead of merely passing each strand from one side of a weft unit to the 20 other side of the adjacent weft unit. An example of the ventilating section of a shade is represented in Fig. 6. Usually the narrow weft units enter into the construction of the ventilating section, and such section is at the 25 upper end of the shade the better to facilitate the egress of the hot air which rises to the ceiling of the porch.

The parts and members thus far described in more or less detail are in and of themselves old and well known. Passing, now, 30 to the new, light-proof construction, and referring more particularly to the first five views, it will be seen that said construction comprises, with a plurality of ordinary warp units 2 and weft units 1, a plurality of specially constructed, auxiliary, weft units 4, or such a weft unit (4) for the space between each pair of weft units 1 in that portion of a shade which it is desired to render light proof. Each of these auxiliary or combined spacing and overlapping weft units is provided on one side in the longitudinal center with an integral flange, rib, or bar, and has upwardly and downwardly 40 extending integral projections or flanges 6-6. The bar or rib 5 and the flanges 6 extend the entire length of the weft unit 4. Thus, in end elevation or cross section, the auxiliary weft unit is generally T-shaped. 45 The rib 5 of each auxiliary weft unit 4 is adapted to be received between the adjacent, longitudinal edges of two of the ordinary weft units 1, and the flanges 6 of said auxiliary weft unit are adapted to extend above 50 and below such edges on one side (the outside) of said ordinary weft units. The thickness of the rib 5 is approximately equal to the combined thickness of one of the weft units 1 and a strand or cord of one of the warp units 2.

Each auxiliary weft unit 4 has a plurality of transverse slots 7 therein. Each slot 7 is cut in the weft unit 4 from the outside thereof to a depth that leaves, between the inner face of the rib 5 of said weft unit and the inner side of said slot which is parallel with said face, a thickness of material that is approximately equal to the thickness of one of the weft units 1. In other words, each slot 7 is cut through the flanged portion 70 of the weft unit 4 into the rib 5 of said weft unit far enough, and only far enough approximately, to leave of the aforesaid thickness that part of said weft unit which is in front of said slot. Such thickness is 80 indicated by the numeral 8 with which the part in question is designated. Provision is thus made for locating the part 8 in the same plane with the weft units 1 during the weaving operation, and for maintaining such part 85 in such position or relationship. There are as many slots 7 in each weft unit 4 as there are warp units 2, and said slots are properly spaced to receive said warp units.

Upon referring to Fig. 4, and following 90 downwardly the course of the two cords or strands of the warp unit 2 therein appearing, the manner in which the parts and members are woven together will be clearly understood. The two warp strands pass 95 downwardly on opposite sides of the part 8 of the uppermost auxiliary weft unit 4, with the outer, which is the left hand, strand in the slot 7 in said weft unit, cross in opposite directions beneath said part and between the 100 same and the ordinary weft unit 1 immediately below, the inner strand then passing to the left and the outer strand to the right, pass downwardly on opposite sides of said ordinary weft unit, cross again in opposite 105 directions, this time below the bottom edge of said ordinary weft unit and between said edge and the upper edge of the part 8 of the next weft unit 4 below, pass down on opposite sides of the part 8 of said second-named auxiliary weft unit, and cross beneath the bottom edge of said last-named part 8, continuing downwardly on opposite 110 sides of the weft units and crossing between the same, until the structure is complete. 115 The weave thus produced corresponds in all essential respects with that commonly used in slat-shade construction. It may be noted, in passing, that the same warp strand passes on the outer sides of the parts 8 and on the 120 inner sides of the weft units 1, while the other strand passes on the inner sides of said parts and on the outer sides of said weft units.

The ordinary weft units 1 are spaced 125 apart from each other a sufficient distance to receive between them the parts 8 of the auxiliary weft units 4 and the cross-overs of the warp units 2, the flanges 6 of said auxiliary weft units are separated from the 130

outer sides of adjacent portions of the ordinary weft units by said warp units, and all of the weft units are maintained in the relative positions described by said warp units.

- 5 It is clearly to be seen, therefore, that air can pass freely between the adjacent edges of the weft units 1 and the ribs 5, and between the adjacent portions of said weft units and the flanges 6, except where the 10 warp units 2 lie between the parts as in the case of the ordinary construction, but that it is impossible for light to pass through from either the outside or the inside of the woven structure, inasmuch as there is no 15 uninterrupted or straight path from one side to the other, and no reflecting surface. It follows, therefore, that a shade or any part thereof which is made up in the manner just described is absolutely light proof yet 20 permits air to circulate through the same.

Without the slots 7 in the auxiliary weft units 4, it would be necessary to carry the warp units 2 over the outside of said weft units, with the result that the weft units 25 would not be properly positioned relative to the associated weft units 1, the structure would be too thick and bulky, and it is doubtful if such structure would be practicable in other respects. By slotting the weft 30 units 4 the above-mentioned objections are overcome. Since the ribs 5 of the weft-units 4 are in the same vertical plane with the weft units 1, the only thickness added to the structure by said weft units 4 is that 35 of the flanges 6.

The auxiliary weft units 4 present no obstacle to the act of rolling the shade structure up or down from or on the inside. This is so because the joints between the 40 weft units 1 and 4 are free to open or expand on the outside, in front of the flanges 6.

In the example herein illustrated, the auxiliary weft units 4 are narrower than the associated weft units 1, but this is of no importance except in so far as a better construction due to such condition may be produced.

The shade illustrated in Fig. 6 comprises an intermediate portion of ordinary construction, with a ventilating portion above and a light-proof portion below, and is ideal for use where it is desired to exclude the light from a bed, and to afford ample ventilation, while at the same time furnishing the necessary protection from observation.

More often, perhaps, a shade such as that illustrated in Fig. 7 will be used. This shade is rendered light proof at the bottom, and is otherwise of the usual ordinary or closely-woven construction. This shade, like the other shade, is useful on sleeping porches, and either is serviceable in excluding the light from a table, and from the porch generally up to the level of the top of the light-proof section. The Fig. 7 shade

being unprovided with a ventilating section is a complete screen throughout its entire height.

The light-proof section need not necessarily be at the bottom of a shade, but may be located therein at any place between the top and bottom thereof, or even at the top if found expedient to do so.

Incidentally, attention is called to the fact that the slots 7 in the auxiliary weft units 4, for the warp units 2, enable the latter to hold said weft units against end lash, and are, therefore, factors which increase the stability and prolong the life of the shade construction.

More or less change in the shape, size, construction and arrangement of some or all of the parts and members of this invention, in addition to those hereinbefore specifically pointed out, may be made without departing from the spirit of said invention or exceeding the scope of what is claimed.

What I claim as my invention, and desire to secure by Letters Patent, is—

1. In shade construction, a weft unit having on one side projecting parts adapted to overlap adjacent edge portions of other weft units, and being transversely slotted through such parts from the plain side.

2. In shade construction, a weft unit having on one side upper and under projections adapted to overlap adjacent edge portions of other weft units, and being transversely slotted through such parts from the plain side.

3. In shade construction, a weft unit having on one side a projection adapted to be received between two other weft units, and on the other side projections which extend above and below said first-named projection, and being transversely slotted through said second-named projections from the plain side.

4. In shade construction, a weft unit having on one side transversely slotted lapping projections substantially as shown.

5. In shade construction, a weft unit having on one side a spacing projection and on the other side transversely slotted lapping projections.

6. In shade construction, a weft unit which is approximately T-shaped in cross section, and has transverse slots opening through the plain side and top and bottom edges.

7. In shade construction, a weft unit having on one side a projection which is receivable between other weft units, and also having projections which extend above and below said first-named projection to overlap said second-named weft units, that portion of said first-named weft unit, which includes said second-named projections, being transversely slotted at suitable intervals.

for the reception of warp units, the slots opening through the plain side and the top and bottom edges of said first-named weft unit.

5 8. In shade construction, two substantially inflexible weft units and flexible warp units therefor, and a substantially inflexible auxiliary weft unit interwoven with said first-named weft units in said warp units, and having a part between said first-named weft units, which part on its exposed face is in approximately the same plane with the adjacent faces of said first-named weft units.

10 9. In shade construction, two weft units and warp units therefor, and an auxiliary weft unit interwoven with said first-named weft units in said warp units, and having parts which overlap said first-named weft units on one side only.

15 10. In shade construction, two weft units and warp units therefor, and an auxiliary weft unit interwoven with said first-named weft units in said warp units, and having parts which enter between and overlap said first-named weft units, the exposed face of the part between the first-named weft units being in approximately the same plane with the adjacent faces of the first-named weft units, and the overlapping parts being on the same side.

20 11. In shade construction, two substantially inflexible weft units and flexible warp units therefor, and a substantially inflexible auxiliary weft unit interwoven with said first-named weft units in said warp units, and transversely slotted to receive the latter, the slots opening through the plain side and the top and bottom edges of said auxiliary weft unit, said auxiliary weft unit having a part received between said first-named weft units, the exposed face of which part is in substantially the same plane with the adjacent faces of said first-named weft units.

25 12. In shade construction, two weft units and warp units therefor, and a substantially inflexible auxiliary weft unit interwoven with said first-named weft units in said warp units, and transversely slotted to receive the latter, the slots opening through the plain side and the top and bottom edges of said auxiliary weft unit, said auxiliary weft unit having a part received between said first-named weft units, and parts that overlap said first-named weft units, the exposed face of the part between the first-named weft units being in approximately the same plane with the adjacent faces of the first-named weft units, and the overlapping parts being on the same side.

30 13. In shade construction, two weft units

and warp units therefor, and a transversely slotted auxiliary weft unit interwoven with said first-named weft units in said warp units, and having on one side a projection 65 that is received between said first-named warp units without extending beyond the same, and projections above and below said first-named projection to overlap said first-named weft units, said last-named projections being on the same side, and said warp units passing between said first-named weft units and said first-named projection on said auxiliary weft unit and through the slots in the latter.

35 14. In shade construction, interwoven warp and weft units, one or more of such weft units extending between, and overlapping on one side only, adjacent weft units to prevent the passage of light therebetween.

40 15. In shade construction, interwoven warp and weft units, one or more of the latter being in intervening and overlapping relation to the others that are immediately adjacent, but separated therefrom by said warp units, whereby light is shut out without excluding air.

45 16. A slat shade comprising interwoven warp and weft units, certain of the latter in a portion of the shade having separating, and lapping parts on one side only which exclude light, but being separated from adjacent weft units so as not to exclude air.

50 17. A slat shade consisting of interwoven warp and weft units arranged to divide the shade into ventilating, ordinary, and light-excluding sections, the weft units in said first-named section being more widely separated than the weft units in said second-named section, and there being auxiliary weft units, in said third-named section, which cooperate with adjacent weft units to prevent the passage of light.

55 18. A slat shade consisting of interwoven warp and weft units arranged to divide the shade into ventilating, ordinary, and light-excluding sections, the weft units in said first-named section being more widely separated than the weft units in said second-named section, and there being auxiliary weft units, in said third-named section, which are separated from adjacent weft units, by said warp units, to admit of the passage of air, and are arranged to cooperate with said adjacent weft units to prevent the passage of light.
